UNITED STATES PATENT OFFICE

TERIJON WEITLING, OF NEW YORK, N. Y.

ANTENNA

Application filed November 30, 1929. Serial No. 410,698.

This invention relates to antennæ of the type capable of use for radio receiving and broadcasting. It has for its object to provide a type of antenna system so arranged and constructed that the same will act to increase volume and greatly clarify radio transmission and reception. Also, while describing the principle which I have discovered, as applied to antenna systems, it will be understood that it may likewise be used in various other embodiments.

With these objects and such other objects as may hereinafter appear, in view, I have devised the particular arrangement of parts hereinafter set forth and more particularly pointed out in the claims appended hereto.

Reference is to be had to the accompanying drawing, forming a part hereof in which

Figure 1 is a diagrammatic view illustrating one embodiment of a structure of my antenna system;

Figure 2 is a longitudinal sectional view of the structure shown in Figure 1;

Figure 3 is a face view illustrating a modified form of variable pick-up structure;

Figure 4 is a sectional view of the plates shown in Figure 3, with a magnet co-operating with such plates;

Figure 5 is a view showing the use of oppositely disposed permanent magnets, creating an intermingling magnetic field with antenna and set terminals disposed in such field;

Figure 6 is a view showing a suggested use of three magnets, with the antenna and set leads connected directly to two of the magnets; and

Figure 7 is another illustrative view showing a suggested use of three magnets, with one of the magnets disposed at right angles to the other two.

Throughout the various views of the drawing, similar reference characters designate similar parts.

In the embodiments of my invention disclosed in the accompanying drawing, I have shown several illustrative forms of my invention. It is possible to utilize my improved structure in many ways, and accordingly, it will be understood that the embodiments

shown in the drawing are merely illustrative of several of the many forms of which my structure is capable of being made.

Referring now to the structure disclosed in Figures 1 and 2. Here is shown at 1 a permanent horseshoe magnet of the well known type. This may be maintained on any suitable support, not shown, and preferably one which will permit the magnet to be moved longitudinally in the directions indicated by the arrows *a*. If desired also, the magnet may be rotated about its longitudinal axis or it may be universally mounted to permit its movement in any direction. The magnet 1 is provided with the conventional poles 2 and 3 between which is disposed a metallic bar 4 or some other metal object or article possessing high conductivity or permeability. In place of a solid metallic bar or other solid conducting object, it may be found desirable to use a bar, sheet or plate composed of a series of layers or laminæ, two examples of which are disclosed in Figures 4 and 5. In Figure 4 the bar 11 is one which is composed of numerous layers 11a which may if desired be made of materials having different degrees of conductivity, such as iron, copper, brass, aluminum, etc. In such case it may be found desirable to physically separate these layers, either by an air space or by insulating separators 12a (Figure 5). Such separators may be of any suitable insulation such as cloth, wood, hard or soft rubber or the like.

The bar 4 whether of single or multiple layers may be arranged to be shifted between the poles 2 and 3 in the directions indicated by the arrows *b* and may also be arranged to be moved along its own and the longitudinal axis of the magnet 1. The bar or other member 4 is preferably provided with a means for receiving a lead-wire, such as a binding post 5 which receives the end of a lead wire 6 that connects to the usual antenna 7 or to any object or article acting as an antenna.

At 8 is shown a bar of single or multiple construction as described in regard to the bar 4, or some other object capable of acting as conductor for the radio circuit. This bar is maintained in such a position that it extends across the poles 2 and 3 of the magnet and

incidentally extends across the end of the bar 4.

It will be noted that the single or multiple bar 8 is held spaced from the portions 2 and 3 of the magnet and incidentally is spaced from the end of the bar 4. The bar 8 is provided with a binding post 9 which receives the end of a wire connection 10 that extends and connects to the antenna binding post of a radio set. The bar 8 is so mounted that it may be shifted longitudinally or it may be shifted to and from the poles 2 and 3 of the magnet as indicated by the arrow c. It also may if desired be shifted so that it will lie angularly with respect to the poles 2 and 3 of the magnet. The bar 8 is provided with a binding post 9 which receives a wire lead 10 that extends from the radio set binding post. I have found that by providing a suitable air gap between two conductors such as the members 4 and 8 in an antenna lead-in and disposing such gap in the field of a magnet results in an increase in volume, in clarity, a possible reduction of static and in an elimination of extraneous noises in radio reception and transmission.

While the magnet 1 is shown to be of the permanent horseshoe type, it will be apparent that the same may readily be of the electro type.

In Figures 3 and 4, I show a modification of my device wherein I disclose a permanent horseshoe type magnet 12 secured upon any support such as at 30, and preferably rotatably mounted as on a spindle 31 or else it may be universally mounted so that it may be shifted in various directions. A multilayer bar or a single conductor 11 similar to that shown at 4 is mounted between the poles of the magnet 12 and this bar 11 carries a wire 13 which extends to the antenna or to any object or device acting as a pick-up medium. Extending across the poles of the magnet but spaced therefrom is a series of segmental shaped plates which when placed together form a disk. These segmental shaped plates indicated by the numerals 14 to 20 inclusive are of various sizes and are spaced from one another by air gaps. They may, if desired be of different metals and thus of different or varying degrees of radio conductivity.

The plates 14 to 20 inclusive may be of multilayer construction and may be fixed in any suitable way upon an insulated support 23 such as is disclosed in Figure 3. Each of the plates carries a binding post 21 which is adapted to be connected to a wire 22 and the various wires indicated at 22 are adapted to be connected together and joined to a single lead-in 35. By either rotating or shifting the position of the magnet 12, its magnetic field may be caused to operate upon one or more of the plates which by reason of their difference in shape and size and material have more or less pick-up capacity.

Through the structure just described and disclosed in detail in Figures 3 and 4, a variation in antenna capacity is readily had by adjusting the position of the magnet with respect to the plates 14 to 20 inclusive and by adjusting the position of the bar 17 relative to the plates and to the poles of the magnet. Various degrees of adjustability and regulation of the parts described can be had to secure the desired results.

In Figure 5 is shown a pair of opposed magnets 36 and 37, the poles of one magnet facing and separated from those on the other. Between these separated magnets is disposed a pair of spaced antenna contacts 38 and 39 which are preferably, although not necessarily, of the layered construction heretofore described. One of these contacts, in the form of a block, bar or sheet may have one, more or all of its layers connected to a wire as at 40 which extends to the antenna or any substitute therefor. The other member 39 connects to a wire 41 which extends to the antenna post on the radio set.

In Figure 6 I have shown three magnets 42, 43 and 44, one leg or pole of each of the magnets 42 being straddled by the poles of the magnet 44. Each of the three magnets is provided with a spindle 45 permitting rotation of any one magnet with respect to the other. The magnets may also be tilted, inclined or shifted in any manner with respect to one another to secure different or variable degrees of intermingling of magnetic forces.

In the structure of Figure 5 I connect the antenna lead 46 directly to the magnet 43 and the set lead 47 directly to the magnet 42. If preferred these leads may be reversed or either of them may be connected to the magnet 44. It is also possible to utilize three or more magnets in various positions with respect to one another and to connect the antenna and set leads to terminals located at any position within the intermingled fields of the various magnets. Something of this character is disclosed in Figure 7.

In Figure 7 three magnets are again shown, the two shown at 49 and 50 being located with their respective poles directed toward one another, and the other magnet 51 being positioned at right angles to the magnets 49 and 50. A bar, block or sheet 52 of single or multi-layer construction is disposed between the poles on the magnets 49 and 50, this element 52 being straddled by the legs of the magnet 51. A bar, block or sheet 52 extends across and is spaced from the poles on the magnet 51. A set lead 54 is connected to the element 53 and an antenna lead 55 is connected to the element 52. Of course, if desired, these connections may be reversed.

I have described several forms of my invention and it will be apparent that the principle found in such embodiments is capable

of incorporation in too many types of structure to permit illustration of them all. Accordingly, I do not limit myself to the several embodiments described but consider as my invention any structure coming within the scope of the annexed claims.

What I claim is:

1. In an antenna system for radio receiving sets, an antenna adapted for connection to a receiver intended for the reception of broadcast sounds, a fixed gap located in the antenna and interrupting the continuity thereof, a magnet of the permanent type so arranged relative to the antenna gap that the magnetic flux of the magnet is disposed therein to bridge the gap and intensify the received signal.
2. In an antenna system for radio receivers, an antenna adapted for connection to a radio receiver, a fixed gap located in the antenna and interrupting the continuity thereof, one or more magnets having their poles directed toward the gap whereby the magnetic flux between the poles acts to bridge the gap and intensifies the received signal.

Signed at the city, county and State of New York, this 29th day of November, 1929.

TERIJON WEITLING.
